UNITED STATES PATENT OFFICE

2,449,763

MUCILAGE CONTAINER

Frank G. Blackman, Bluefield, W. Va.

Application June 29, 1945, Serial No. 602,299

2 Claims. (Cl. 222—425)

1

The present invention relates to new and useful improvements in containers for mucilage and similar liquid and semi-liquid material which is affected by contact with the air to cause evaporation or coagulation thereof, and the invention has for its primary object to provide a mucilage-dispensing container by means of which a desired quantity of mucilage may be exposed and made available for use without subjecting the remaining contents of the container to the action of air.

A further object of the invention is to provide a dispensing container of this character embodying a mucilage receptacle having a supply pipe connected thereto leading from a reservoir for supplying a desired quantity of mucilage to the receptacle and providing a hinged cover for the top of the receptacle within which a mucilage brush or applicator may be suspended in the receptacle to prevent hardening of the brush when not in use, and also which provides a substantially air-tight closure for the open top of the receptacle.

A further object of the invention is to provide a device of this character of simple and practical construction, which is efficient and reliable in operation, neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a vertical sectional view.

Figure 2 is a transverse sectional view taken substantially on a line 2—2 of Figure 1.

Figure 3 is a vertical sectional view through the cover for the mucilage receptacle, taken substantially on a line 3—3 of Figure 1.

Referring now to the drawing in detail, wherein for the purpose of illustration I have disclosed a preferred embodiment of the invention, the numeral 5 designates a reservoir adapted to hold a predetermined quantity of mucilage 6 and having a hinged lid 7 at its top adapted to provide a substantially air-tight closure for the reservoir.

A discharge pipe 8 is connected to the bottom of the reservoir and projects outwardly at one side thereof and to which is attached a receptacle 9, the pipe 8 having a manually controlled valve 10 therein.

A vertically extending web 11 is formed at one side of the reservoir 5 and to the outer edge of

which are hingedly attached the vertical split edges of a pair of semi-cylindrical cover sections 12 and 13 arranged in a vertical position and adapted for closing about the sides of the receptacle 9, as indicated in Figure 1 of the drawing.

The cover sections 12 and 13 are formed with overlapping top sections 14 and 15, respectively, adapted to close the top of the cover for the receptacle 9 and the free vertical edges of the cover sections 12 and 13 are secured in closed position in tight fitting clamping engagement with the sides of the receptacle 9 by means of a conventional form of fastener 16.

One upper edge of the receptacle 9 is formed with a lip 17 adapted for wiping excess mucilage from a brush 18 when used for applying the mucilage to the work.

When the brush is not in use, the handle thereof is hung from a hook 19 attached at the hinged edges of the sections 12 and 13 so that the bristles of the brush may be suspended in the mucilage in the receptacle 9 to prevent drying or hardening of the brush.

In the operation of the device, a desired quantity of the mucilage is admitted into the receptacle 9 through the pipe 8 and valve 10 and the remaining mucilage contained in the reservoir 5 is then kept in a closed condition out of contact with the air.

When it is desired to use the mucilage from the receptacle 9, the cover sections 12 and 13 are swung into open position and the brush 18 may then be removed for applying the mucilage to the work. When the brush is not in use, the same is hung from the hook 19 within the cover sections 12 and 13 and the cover sections closed, as shown by the full lines in Figure 2 of the drawing, whereby the contents of the receptacle 9 will likewise be substantially sealed against contact with the air.

It is believed that the details of construction, manner of use and advantages of the device will be readily understood from the foregoing without further detailed explanation.

It is to be understood, however, that even though I have herein shown and described a preferred embodiment of my invention, the same is susceptible of certain changes fully comprehended by the spirit of the invention as herein described, and the scope of the appended claims.

Having thus described the invention, what I claim is:

1. A device of the class described comprising a reservoir adapted to contain liquid and having a substantially air-tight lid, a cylindrical recep-

tacle, a feed pipe connecting the reservoir to the receptacle and having a valve therein to admit a limited volume of liquid to the receptacle, and a pair of hingedly connected semi-cylindrical cover sections closed at their tops and adapted for closing against the sides of the receptacle in tight fitting engagement therewith, and means within the cover sections for suspending a brush in the liquid of the receptacle.

2. A device of the class described comprising a reservoir adapted to contain liquid and having a substantially air-tight lid, a cylindrical receptacle, a feed pipe connecting the reservoir to the receptacle and having a valve therein to admit a limited volume of liquid to the receptacle, a ver-

tical web projecting from one side of the reservoir, and a pair of semi-cylindrical cover sections having overlapping tops and hingedly connected to said web for closing against the sides of the receptacle in tight fitting engagement therewith.

FRANK G. BLACKMAN.
